UNITED STATES PATENT OFFICE

2,048,085

DEEP WELL PUMP

Richard N. Vickers, Smackover, Ark.

Application November 6, 1934, Serial No. 751,751

1 Claim. (Cl. 103—155)

This invention relates to an improved deep well pump and more particularly to improvements in the pump shown in Patent No. 1,864,914 granted to F. C. Kniss and myself June 28, 1932.

The present invention seeks, among other objects, to effectively pack off the hydrostatic pressure of the fluid in the tubing from the standing valve while eliminating the use of close-fitting telescopic parts.

10 A further object of the invention in this connection is to provide a soft or ductile bushing for packing off the hydrostatic pressure of the fluid in the tubing, wherein the weight of the rods, when the valve assembly is lowered into position, will serve to press the bushing into engagement with its seat to form a sealed joint therewith, and wherein the bushing will then serve to frictionally hold the valve assembly stationary when the pump is in operation.

20 A further object of the invention is to provide a pump wherein the discharge valve will be closely confined to travel in a path axially of the valve seat so that lateral floating of the valve and consequent escape of fluid before the valve closes or rapid cutting of the seat will be obviated.

25 And the invention seeks as a still further object to provide a pump wherein the valve assembly and plunger may be readily installed or removed as a unit without likelihood of the parts becoming disconnected.

30 Other and incidental objects of the invention will appear as the description proceeds and in the drawing forming part of this application.

35 Figure 1 is a vertical sectional view of my improved pump.

Figure 2 is an enlarged fragmentary section particularly showing the bypass tube of the valve assembly, and

40 Figure 3 is a transverse sectional view on the line 3—3 of Figure 2 showing the centering ribs on the wall of the discharge valve chamber of the bypass tube.

45 Referring now more particularly to the drawing, I have shown a well tubing or casing at 10 and in carrying the invention into effect, I employ a tubular jacket 11 which is screwed at its upper end onto the lower end of the casing. Screwed into the lower end of the jacket is a nipple 12 and this nipple is externally threaded at its lower extremity to receive a suitable strainer, not shown. Near its upper end, the jacket 11 is thickened internally to provide a seat 13 stepped to form an annular shoulder 14 and this shoulder may be either flat or bevelled as may be preferred. In 50 the present instance I have shown a flat shoulder.

5 Disposed within the jacket 11 is a bypass tube 15 provided at its upper end with a collar 16 and tightly fitting about the tube to abut said collar is a bushing 17 of soft metal such as lead or babbitt. The bushing 17 is preferably bonded to the tube and below said bushing the tube is reduced slightly in external diameter to slide through the seat 13 of the jacket 11 at the shoulder 14. As will be observed, the collar 16 and bushing 17 fit the seat 13 while the bushing rests flat at its lower 10 edge upon the shoulder 14 for sustaining the bypass tube 15 in position axially of the jacket to define an annular chamber 18 between the tube and jacket, the combined height of the bushing 17 and the collar 16 having a substantial frictional contact with the inner vertical wall of the seat 13 as to preclude lateral displacement of the bypass tube with relation to the jacket.

Near its lower end, the tube 15 is provided with an internal annular stop flange 19 above which 20 is a discharge valve chamber 20 and formed on the wall of said chamber to lie parallel to the axis of the tube is an annular series of spaced centering ribs 21. Lying between the ribs 21, as particularly seen in Figure 3, is a series of grooves 25 22 which extend longitudinally of the valve chamber 20.

Extending diametrically of the tube 15 at the upper end of the chamber 20 is a duct 23 providing a transverse passage 24 opening through the 30 wall of the tube at opposite sides thereof and rising from said duct is a tubular stem 25 providing a cylindrical chamber 26 communicating with the passage 24. The stem 25 is disposed axially of the tube 15 and at the upper end of said tube is 35 thickened externally to provide a head 27 carrying a stud 28. Extending at opposite sides of the duct 23, as particularly seen in Figure 1 are passages 29 establishing communication between the valve chamber 20 and the upper end portion of 40 the tube 15.

45 Abutting the stop flange 19 is a valve seat 30 and normally resting on said seat is a ball discharge valve 31 centered within the chamber 20 by the ribs 21. Only slight clearance is provided 45 between the ball and ribs so that the ball will be confined to travel substantially in a straight path axially of the valve seat. Lateral floating of the valve and consequent escape of fluid before the valve closes or rapid cutting of the seat is thus 50 obviated while, however, liquid is permitted to freely flow through the valve chamber 20 within the grooves 22.

55 Screwed into the lower end of the bypass tube 15 is a standing valve cage 32 in which is fixed 55

a seat 33 and confined within the cage is a ball standing valve 34 limited in its upward movement by a spider 35. Screwed into the lower end of the cage 32 is a cup tube 36 and mounted on said tube are suitable cups 37 which more or less tightly fit the nipple 12. Thus, as will be seen, these cups pack off the well pressure from the chamber 18 externally of the tube 36.

Screwed onto the stud 28 of the stem of the by-pass tube 15 is a standing tube 38 thickened internally near its lower end to provide a tapered seat 39 having a left-hand thread. Reciprocable in said tube is a plunger 40 provided at its lower end with a tapered stud 41 adapted to be screwed into the seat 39 and screwed onto the upper end of said plunger is a head 42 to which the usual pump rods are attached. Screwed onto the lower end of the head 42 is a skirt or traveling tube 43 which telescopically fits snugly over the standing tube 38. A chamber 44 is thus defined above the upper end of the standing tube within the upper end portion of the traveling tube.

At its upper end, the plunger 40 is bored to provide a passage 45 from which lead ports 46 communicating with the chamber 44 and formed in the head 42 to communicate with the passage 45 is an axially aligned passage 47. Leading from the upper end of the passage 47 to the exterior of the head are ports 48 and confined between the head and the upper end of the plunger 40 is a valve seat 49 with which is arranged to coat a ball check valve 50. Thus, when the plunger 40 and traveling tube 43 move downwardly, fluid in the chamber 44 will be permitted to escape through the ports 46, passage 45, passage 47 and ports 48. On the upstroke of the plunger however, the valve 50 will close so that the fluid in the chamber 44 will be retained therein to provide a seal between the traveling tube 43 and the standing tube 38.

Attention is now directed to the fact that the stud 41 of the plunger 40 may be screwed into the socket 39 of the standing tube 38, when the entire valve assembly may be lowered into the well as a unit and the bushing 17 seated upon the shoulder 14 of the seat 13. As the bushing 17 is thus initially seated, the weight of the rods will serve to press the bushing downwardly into engagement with the seat and as said bushing is of soft metal, as previously noted, the bushing will be mutilated to tightly conform to the surface of the shoulder 14 and will also be expanded to frictionally grip the wall of the seat 13. The bushing will thus serve to effectively pack off the hydrostatic pressure in the well tubing 10 and exclude such pressure from the chamber 18 so that the standing valve 34 may operate freely. Furthermore, the bushing 17 will, in gripping the wall of the seat 13, hold the valve assembly and connected parts stationary while the plunger 40 is in operation.

After the valve assembly has been lowered into position, as just previously described, the plunger 40 is turned to unscrew the stud 41 from the seat 39, thus freeing the plunger. The plunger is then elevated, as shown in Figure 1, when

the pump is ready to function. Should it prove desirable or necessary, however, to remove the valve assembly at any time, the stud 41 is again screwed into the socket 39 when the entire valve assembly may, as will now be appreciated, be withdrawn as a unit.

Upon the upstroke of the plunger 40, fluid is drawn upwardly through the tube 36 and cage 32 into the chamber 18 and thence through the passage 24 of the bypass tube 15 and into the chamber 26 and standing tube 38. Upon the downward stroke of the plunger 40, the standing valve 34 closes, when the fluid is forced from the standing tube 38 and chamber 26 back through the passage 24 into the chamber 18 and thence back through the cage 32 and upwardly through the valve chamber 20 and passages 29 of the bypass tube 15 to enter the lower end of the well tubing through said tube. As the plunger 40 next starts upwardly, the discharge valve 31 will, of course, close while the standing valve 34 will be opened and the cycle repeated. I accordingly provide a particularly effective pump for deep well use and wherein the standing valve is relieved of well pressure such as might tend to hold the valve closed and is also relieved of hydrostatic pressure in the well tubing so that the standing valve may freely function at all times.

Having thus described the invention, I claim:

A deep well pump including a jacket adapted for attachment to a well tubing and provided with an internal reduced portion adjacent the upper end thereof, a jutting right angle shoulder arranged at the base of said reduced portion, a bypass tube supported within the jacket by said jutting shoulder to define a chamber between the tube and jacket and provided with a discharge valve chamber, said tube being provided with a collar, a soft metallic bushing bonded to the tube to abut said collar and resting at its lower edge against said shoulder, the outer faces of said collar and bushing being of sufficient height to have a substantial frictional contact with the inner face of the reduced portion of the jacket to preclude lateral displacement of the bypass tube with relation to the jacket, said bushing being constantly urged by the weight of the liquid in the well tubing against the shoulder to be distortedly expanded by said shoulder into tight intimate engagement with said jutting shoulder forming a seal between the seat and tube, a standing tube connected with said bypass tube, a plunger reciprocable in said standing tube, the bypass tube being provided with a passage establishing communication between the standing tube and said first mentioned chamber as well as with a passage establishing communication between said discharge valve chamber and the well tubing, a discharge valve in said discharge valve chamber, a standing valve cage connected with said bypass tube and communicating with said first mentioned chamber as well as with said discharge valve chamber, and a standing valve in said cage.

RICHARD N. VICKERS.
